UNITED STATES PATENT OFFICE.

JOSEPH LOCKE, OF TOLEDO, OHIO, ASSIGNOR TO THE W. L. LIBBEY & SON COMPANY, OF SAME PLACE.

DESIGN FOR THE ORNAMENTATION OF GLASSWARE.

SPECIFICATION forming part of Design No. 19,847, dated October 8, 1889.

Application filed June 7, 1889. Serial No. 313,508. Term of patent 7 years.

To all whom it may concern:

Be it known that I, JOSEPH LOCKE, a citizen of the United States, residing at Toledo, in the county of Lucas and State of Ohio, have invented a certain new and original Design for the Surface Ornamentation of Glassware; and I do hereby declare that the following is a full, clear, and exact description of the invention, which will enable others skilled in the art to which it appertains to make and use the same, reference being had to the accompanying drawings, and to the letters of reference marked thereon, which form part of this specification.

15 The class to which this design relates is that of ornamentation of glassware; and the design pertains to the surface ornamentation of the ware to which it is applied, being applicable to all kinds of glassware shaped similar to the dish shown in the accompanying drawings.

20 In the drawings, in which Figure 1 is a side elevation and Fig. 2 a longitudinal vertical section, I have shown a circular dish formed with a surface ornamentation in accordance with my design.

25 The leading features of my design are a representation of spiral strands intertwined to form the appearance of a twisted rope. 30 The ropes thus formed are extended from the base to the top of the dish, circumferentially

of the same, with each rope inclining vertically from the base to the top of the dish. To harmonize the design with the particular contour of the dish to which it is applied, the 35 rope is formed of greater area centrally in cross-section than at either or both ends. In the dish chosen for illustration, the center being of greater diameter than either the top or bottom to harmonize the design therewith, 40 I form each representation of rope of greater area in cross-section centrally of the length than at either end thereof, thereby preserving the parallelism of the same.

A designates a dish; B B, the intertwined 45 strands, which form the representation of a section of rope C in parallel relation circumferentially of the dish, the ropes being formed upon the surface of the same spirally, as suggested, of and in harmony with the spirality 50 of the intertwined strands forming the rope.

What I claim is—

The design for the ornamentation of glassware, substantially as herein shown and described.

In testimony that I claim the foregoing as my own I hereby affix my signature in presence of two witnesses.

JOSEPH LOCKE.
